UNITED STATES PATENT OFFICE,

CHARLES FREDERICK GEDNEY, OF BROOKLYN, NEW YORK, ASSIGNOR TO MATTHEW J. WHITTALL, OF WORCESTER, MASSACHUSETTS.

DESIGN FOR CARPET.

SPECIFICATION forming part of Design No. 24,649, dated August 27, 1895.

Application filed July 30, 1895. Serial No. 557,640. Term of patent 3½ years.

To all whom it may concern:

Be it known that I, CHARLES FREDERICK GEDNEY, residing at Brooklyn, county of Kings, State of New York, have invented and 5 produced a new and original Design for a Pattern to be Wrought into Carpets, in such coloring as may be designed; and I do hereby declare that the drawing accompanying this specification gives and conveys to any one 10 skilled in the art of carpet weaving and manufacture a clear understanding of the same and is sufficient to enable such person to use my invention.

The design consists of the body A and the 15 border B.

The body A shows clusters of the wild rose and its foliage, appearing with openwork scrolls.

In the border B there is also the wild-rose flowers and foliage in vine form, with similar 20 scrolls, and an outer edge of the rose blossoms with ferns.

What I claim as my invention, and desire to secure by Letters Patent, is—

1. In a design for carpet, the body A, substantially as shown.
2. In a design for carpet, the border B, substantially as shown.
3. The design for carpet, consisting of the body A, and the border B, substantially as 30 shown.

CHARLES FREDERICK GEDNEY.
